(No Model.)

C. TEMME.
Stove Leg Fastening.

No. 233,382.

Patented Oct. 19, 1880.

FIG. 1.

FIG. 2.

ATTEST:

Robert Burns
Geo Bullock

INVENTOR:

Christian Temme

UNITED STATES PATENT OFFICE.

CHRISTIAN TEMME, OF ST. LOUIS, MISSOURI.

STOVE-LEG FASTENING.

SPECIFICATION forming part of Letters Patent No. 233,382, dated October 19, 1880.

Application filed May 28, 1880. (No model.)

To all whom it may concern:

Be it known that I, CHRISTIAN TEMME, of the city of St. Louis, in the State of Missouri, have invented certain new and useful Improvements in Stove-Leg Fastenings; and I do hereby declare the following to be a full, clear, and exact description of the same, reference being had to the accompanying drawings, and to the letters of reference marked thereon.

10 This invention relates to an improved device for securely locking and holding stove-legs of the ordinary construction in place after they have been placed in position under a stove; and this invention consists in the combination, with the stove-legs secured in the ordinary way to the bottom of the stove, of border or tie pieces bolted to side lugs on the legs after they have been placed in position under the stove, the purpose being to lock 15 and firmly hold the legs in position and prevent them from being detached in moving the stove, &c.

In the drawings, Figure 1 is an under perspective view illustrating my invention. Fig. 25 2 is a detail bottom plan, partly in section.

The stove-legs A are secured to the bottom of the stove B by means of their toes *a* engaging between the bevel-faced lugs *b* on the bottom of the stove in the usual manner.

30 The stove-legs have side lugs, *a'*, to which

the ends of the border or tie pieces C are securely attached by bolt and nut *c*, or their equivalent.

The border-pieces are formed with shoulders *c'* *c''*, which engage the sides of the stove-legs 35 to form a stiff and rigid joint at these points. The shape of the border-pieces C will be varied to suit the configuration of the bottom part of the stove, to which my improvement is applied.

40 In the drawings I have shown it applied to the ordinary square-bottom cooking-stove.

The main advantage of my improved construction is, that by its use the stove-legs are securely attached to the stove, so as to form 45 an integral part of the same, and so that no amount of movement or handling of the stove will displace or loosen the legs.

I claim as my invention—

The stove-legs A, fastened in the usual manner to the bottom of the stove, in combination with the tie or border pieces C, for the purpose set forth.

In testimony whereof, witness my hand this 26th day of May, A. D. 1880.

CHRISTIAN TEMME.

In presence of—

ROBERT BURNS,
GEO. BULLOCK.
